CEILING TILE

Hobart Woodward, 5512 S. 10th Ave.,
Minneapolis, Minn.

Filed Feb. 12, 1963, Ser. No. 73,524

Term of patent 14 years

(Cl. D18—2)

FIG. 1

FIG. 2

FIG. 3

FIGURE 1 is a top plan view of a ceiling tile showing my design;

FIGURE 2 is an edge view of said ceiling tile;

FIGURE 3 is a sectional view taken on line 3—3 of FIGURE 1.

In FIGURE 1 the rear of the ceiling tile is substantially plain.

I claim:

The ornamental design for the ceiling tile, substantially as shown and described.
